MATRIX SETTING AND TYPE-LINE-CASTING MACHINE

Kurt Bendorff, Berlin, Germany, assignor to the firm Typograph G. m. b. H., Berlin, Germany

Application February 6, 1939, Serial No. 254,958
In Germany February 16, 1938

12 Claims. (Cl. 199—60)

The invention relates to a type line ejecting device for matrix setting and type line casting machines permitting particularly rapid and easy change of size. Heretofore, for example, in machines with matrix bars guided on wires, it has been necessary for changing the type line ejector not only to remove its entire carrier from its guide arranged near the hot casting pot in the machine frame, after undoing the helical spring urging it into its position of rest, but thereupon it has been necessary to unscrew two screws completely out of their screwthreaded holes in order to be able to insert the new type line ejector, secure it and then, together with the carrier, introduce it into the machine again and connect it to the tension spring holding it fast.

In contrast thereto, the new type line ejecting device, which is also advantageously applicable to machines equipped with other matrices is by means of a handle, readily accessible from the rear and precludes any danger of burning for the compositor, even in the case of a hot casting pot, a light pressure against a hand lever being sufficient, to permit removal and re-insertion of ejector plates without having to undo springs or screws for this purpose or even having to remove the entire ejector carrier from its guide in the machine.

According to the invention, in the new type line ejecting device, this object is accomplished by the fact that cams, which are pivotally mounted on the ejector carrier, slidably guided in the machine, are adapted to be operated by means of a hand lever under the action of a spring which engages said lever—conveniently the tension spring that simultaneously also presses the entire ejecting device, i. e. the carrier and ejecting plate, towards the position of rest—and press firmly in the operative position the ejecting plate which is guided by means of slots on pins secured to the ejector carrier. These cams may be mounted individually on a shaft pivoted in the ejector carrier or they may be made integral with said shaft. In order to ensure satisfactory sliding away of the waste, that is to say, the tang separated after cooling of the type line, it is necessary to chamfer the cam discs with an outward inclination so that pieces of waste cannot remain on them or find their way between the parts of the ejecting device. Conveniently, however, in place of the shaft carrying the cams, a bar of substantially prismatic shape pivotally mounted in the ejector carrier by means of two lateral pivots is employed, the upper rear face of said bar, which

extends throughout the entire length of the type line ejector and also prevents the penetration of lead cuttings into the ejecting device, being chamfered with an outward inclination in a manner ensuring satisfactory sliding away of the separated type line tang.

The invention is illustrated diagrammatically in the accompanying drawing with reference to an ejecting device, selected as a constructional example, for a matrix setting and type line casting machine equipped with matrix bars guided on wires. In the drawing:

Figure 1 shows an elevation of type line ejecting device in the position ready for operation.

Figure 2 shows a section on the line II—II of Figure 1.

Figure 3 shows the same section as Figure 2, but in the release position of the cams after the ejecting plate has been moved away.

Figure 4 shows a section on the line IV—IV of Figure 1.

Figure 5 shows the elevation of a type line ejecting plate removed from the device.

Figure 6 shows the elevation of the carrying frame for receiving the ejecting plate, the cam shaft having been removed, and

Figure 7 shows the plan of a substantially prismatic bar carrying the cams.

In the bridge 1 moved by the machine in a mainly vertical direction, the frame-shaped carrier 3, receiving the ejecting plate 2, is guided by means of its two pins 4, the lower free ends of which engage in known manner by means of dove-tail grooves 5 corresponding slides 7 secured to the machine frame 6. In the base ledge 8 of the ejecting plate 2 corresponding to the type lines to be cast are receiving slots 10 (Figure 5) which are downwardly open (in the operative position), are provided with chamfered edges 9 and engage guide pins 11 (Figure 6) secured to the carrier 3 and having a diameter corresponding exactly to the width of the slots 10. The thickness of the base ledge 8 projects slightly beyond the top of the guide pins 11, so that the latter are always in a sunk position in the guide slots 10 of the base ledge 8 of the ejecting plate 2. These slot and pin connections 10, 11 serve for the lateral guiding of the ejecting plate 2 in its longitudinal direction, while in the operative position, the plate 2 bears with its base ledge 8 against the supporting edge 12 of the carrier 3. On the side opposite the pins 11 of the carrier 3 cams 13 are so arranged on a connecting piece 15 pivoted in the frame of the carrier 3 by means of pivots 14, 14' that in the operative position 55

(Figure 2), under the action of a spring, advantageously of a tension spring 19 secured by one end to an eye 16 on the bridge 1 and by its other end to an arm 18 secured to the connecting piece 15 and projecting for instance through a slot 17 in the bridge 1, they press firmly against the ejecting plate 2 situated in the carrier 3. In consequence of such an arrangement, the spring 19 performs both the function of bringing the ejector carrier 3 and the bridge 1 into their position shown in Figure 1 after their release by the machine, and also of holding the ejecting plate 2 firmly in its operative position (Figures 1 and 2) through the connecting piece 18, 15 by means of the cams 13.

The cams 13 may be secured to a common shaft mounted in the frame of the carrier 3 or may be made integral with said shaft. Their upper rear faces 20 are chamfered with an outward inclination so that no separated type line tang waste will remain resting thereon but will slide off satisfactorily. Advantageously, as will also be seen from the drawing, the cams 13 are formed as part of a substantially prismatic bar 15 connecting them together and adapted to rock about its end pivots 14, 14' in the carrier 3, the outwardly and downwardly inclined rear face 20 thereof, which extends throughout the entire length of the ejecting plate 2 and is brought close up to the latter, ensuring not only the satisfactory sliding off of the separated type line tang, but at the same time also preventing small pieces of lead from falling in between the parts of the ejecting device. Mounted on the rearwardly positioned pivot 14' of the cam carrier 15, the said pivot being extended beyond its bearing point, is a hand lever 21, by turning which in the direction of the arrow A in Figure 2 the bar 15 is rotated and the cams 13 secured to it are moved away from the base ledge 8 of the ejecting plate 2 against the action of the spring 19, so that the ejecting plate may be readily removed in the upward direction. When the parts are in this position of release, it is possible without difficulty to insert an ejecting plate 2, 8, corresponding to another size over the pins 11 until it bears against the supporting edge 12 of the carrier 3, which plate, after the release of the hand lever 21 is pressed by the cams 13 under the action of the spring 19 against the frame and supporting edge 12 of the carrier 3 and is there held fast in its operative position.

Having thus fully described the invention what is claimed as new and desired to be secured by Letters Patent is:

55. 1. A type line ejecting device for matrix setting and type line casting machines including supporting means, an ejecting plate vertically disposed on and removably interengaged with said supporting means, and manually operable spring pressed clamping means for releasably exerting downward and inward pressure on and for holding said ejecting plate in an upright position on the supporting means.

55. 2. A type line ejecting device for matrix setting and type line casting machines including supporting means, guiding means in which the supporting means is slidable, an ejecting plate removably mounted on said supporting means, and manually operable spring pressed clamping means for releasably holding said ejecting plate in an upright position on the supporting means, said latter means being operatively connected with the guiding means for yieldingly connecting the guiding means to the supporting means.

75. 3. A type line ejecting device for matrix set-

ting and type line casting machines including an ejector carrier slidably guided on the machine, guide pins on the said carrier, an ejecting plate having a base ledge provided with slots therein for removable engagement with the guide pins 5 on the ejector carrier, a series of cams pivotally mounted on the ejector carrier, spring pressed means operatively connected with said cams for pressing said cams against the base ledge of the said ejecting plate, and operating means for moving the cams away from the carrier and against the tension of the spring pressing means to release the ejecting plate.

4. A type line ejecting device for matrix setting and type line casting machines including an ejector carrier mounted on the machine, an ejecting plate removably mounted on the said ejector carrier, a shaft pivotally mounted on the said ejector carrier in front of the said ejecting plate, a series of cams mounted on the said shaft, an arm connected to the said shaft, manually operable spring pressed means associated with the said arm for releasably pressing the said cams against the ejecting plate thereby holding it in an upright position on the ejector carrier.

25. 5. A device as claimed in claim 4, in which the upper rear faces of the cams are inclined outwardly and sharply downwardly to serve as a deflecting path for type line waste.

30. 6. A type line ejecting device for matrix setting and type line casting machines including an ejector carrier slidably guided on the machine, an ejecting plate removably mounted on the said ejector carrier, a prismatic bar carrying a series of cams and journalled at its ends in the ejector 35 carrier, said bar extending throughout the entire length of the ejecting plate and having its upper face inclined outwardly and sharply downward as a deflecting path for type line waste, and means to yieldingly and releasably hold said cams 40 against said ejecting plate to maintain the latter in an upright position on the ejector carrier.

7. A type line ejecting device for matrix setting and type line casting machines, including an ejector carrier, guide pins on said ejector carrier, 45 an ejecting plate provided with a base ledge having slots therein for receiving the guide pins on the ejector carrier, the said pins terminating short of the outer face of the base ledge, and manually operable spring pressed clamping 50 means for releasably holding the said ejecting plate in an upright position on the ejector carrier.

8. A type line ejecting device for matrix setting and type line casting machines including an ejector carrier slidably guided in the machine, 55 a bridge member mounted on the machine and guiding the ejector carrier, an ejecting plate removably mounted in the said ejector carrier, and manually operable spring pressed clamping means 60 for releasably holding the ejecting plate in an upright position on the ejector carrier.

9. A type line ejecting device for matrix setting and type line casting machines including supporting means, an ejecting plate removably mounted 65 on the said supporting means, a rod member pivotally mounted on the said supporting means in front of the ejecting plate, a series of cams provided on the said rod member and pressing against the said ejecting plate, an arm mounted 70 at one end on the rod member, a tension spring connected at one end to the free end of the said rod member and at the outer end to the supporting means for holding said cams in the clamping position, and a hand lever for turning said rod 75.

member against the action of the spring to release the cams from their clamping position.

10. A type line ejecting device for matrix setting and type line casting machines, including an 5 ejector carrier, a slotted bridge member mounted on the machine and guiding the ejector carrier, an ejecting plate removably mounted on the ejector carrier, a rod member extending the length of said ejecting plate, pivotally mounted 10 relatively to the ejector carrier, a series of cams mounted on the said rod member and pressing against said ejecting plate, an arm connected at one end to the rod member and having its free end passing through the slot in the bridge member, 15 a tension spring connected at one end to the free end of the said arm at its other end to the bridge member for holding the said rod and the cams carried thereon in clamping engagement with the ejecting plate, and a hand lever for 20 moving the said rod member about its pivot thereby moving the cams away from the ejecting plate.

11. A type line ejecting device for matrix setting and type line casting machines including an ejector carrier mounted on the machine, an ejecting plate removably mounted on the ejector carrier, a substantially prismatic bar pivotally 5 mounted on the ejector carrier in front of the ejecting plate, a series of cams provided on the said prismatic bar and bearing against the said ejecting plate, and manually operable spring pressed means connected to said prismatic bar 10 for releasably holding the said cams in clamping engagement with the ejecting plate.

12. A type line ejecting device as claimed in claim 1, characterized in that the ejecting plate, secured only in its longitudinal direction by 15 means of the slot and pin guide, bears in the operative position with its base ledge firmly against a supporting surface provided on the carrier.
